UNITED STATES PATENT OFFICE.

GEORGE CORRIE BARTRAM, OF MASSAPEQUA, NEW YORK, ASSIGNOR TO UNITED CONCRETE PIPE CO., OF NEW YORK, N. Y., A CORPORATION OF DELAWARE.

REINFORCED-CONCRETE PIPE.

1,346,629.

Specification of Letters Patent. Patented July 13, 1920.

Application filed October 25, 1919. Serial No. 333,201.

To all whom it may concern:

Be it known that I, GEORGE CORRIE BARTRAM, a citizen of the United States of America, residing at Massapequa, in the county of Nassau, Long Island, New York, have invented certain new and useful Improvements in Reinforced-Concrete Pipes, of which the following is a specification.

My invention relates to reinforced concrete constructions and particularly to constructions in which the reinforcement comprises an imperforate sheet or shell, such as used, for example, in pipes, tunnels, reservoirs, and the like, to seal the same against the escape of contained water or gas.

In the accompanying drawings—

Figure 1 is a longitudinal elevation partly in section of portion of a pipe in which my invention is embodied in one form;

Fig. 2 is a transverse sectional elevation thereof;

Fig. 3 is a development of the element of the reinforcing members to which my invention particularly relates; and

Fig. 4 is a similar view of a modified construction.

In certain reinforced concrete constructions, such as water and gas pipes, tunnels, reservoirs, etc., it has been proposed to use sheet metal cylinders which are embedded in the concrete and serve to seal the pipe against the escape of liquid or gas therethrough. Under the influence of changes in temperature, vibration, etc., it frequently occurs, however, that the concrete becomes loosened from the metal and peels or breaks away, thus exposing the metal pipe and weakening the structure. The present invention provides means by which the concrete may be tied to the reinforcing sheet metal pipe, while at the same time preserving the latter imperforate, and thus insuring a gas- and fluid-tight seal.

The invention is shown applied to a reinforced concrete pipe having a sheet metal pipe 5 embedded in the concrete 6. At suitable intervals on both the inner and outer faces of the pipe are welded thereto any suitable means, such as wires 7, the free ends of which extend into the concrete and effectively tie the latter to the sheet metal pipe 5. In Fig. 3 the wires are double ended, being welded to the pipe at their mid points 8. In Fig. 4 they are welded at one end to the pipe. Any other desired tie means may be

employed which does not involve perforating the pipe, and is of such character that it will serve to tie the concrete to the pipe. Obviously, if tie means are needed on only one face of the pipe, then those for the other 60 face may be omitted.

In the construction illustrated I have shown a mesh reinforce 9, of common type, with circumferential rings or coils 10, to which the tie wires 7 are fastened at their 65 outer ends. In this construction the tie means not only secure the concrete to the pipe, but also properly maintain the position of the mesh reinforce with relation to the sheet metal pipe 5. Here again, the use 70 of a mesh reinforce on both the inner and outer faces of the metal pipe 5 is optional, one or the other being sufficient under certain conditions, in which case the tie wires would extend into the concrete without 75 engaging any other reinforce and having solely the function of tying the concrete to the sheet metal pipe 5.

The welding operation by which the tie means are secured to the face of the pipe 5 80 may be of any suitable type, for example, electrical or acetylene, or the attachment of the tie means to the pipe may be otherwise accomplished so long as the pipe 5 maintains its imperforate condition.

In the following claims, the word "pipe" is used in a sense broad enough to include such structures as tunnels, tanks, etc., and the word "imperforate" in a sense broad enough to include a structure in which the 90 pipe comprises plates riveted or welded together at their edges in a water- or gas-tight joint. The underlying thought of the invention is to apply to the imperforate bodies of the plates, or to the imperforate wall of a 95 one-piece metal pipe, suitable tie means for holding the concrete while at the same time maintaining these plates or walls free from leakage apertures.

I claim as my invention—

1. A reinforced concrete pipe having an imperforate metal pipe embedded therein, and tie means mechanically connected to the face of the metal pipe and extending into the concrete to tie the latter thereto.

2. A reinforced concrete pipe having an imperforate metal pipe embedded therein, and tie means welded to the face of the pipe and extending into the concrete to tie the latter thereto.

110

3. A reinforced concrete pipe having an imperforate metal pipe embedded therein, and tie means welded to both faces of the pipe and extending into the concrete to tie the latter thereto. 20
4. A reinforced concrete pipe having an imperforate metal pipe embedded therein, and tie means mechanically connected to the face of the metal pipe and extending into the concrete to tie the latter thereto, in combination with open reinforcing elements spaced from the pipe and embedded in the concrete, said open reinforce being engaged by the tie means attached to the face of the pipe. 10
5. A reinforced concrete pipe having an imperforate metal pipe embedded therein, and tie wires welded to the face of the pipe 15
- and extending into the concrete to tie the latter thereto. 21
6. A reinforced concrete pipe having an imperforate sheet metal pipe embedded therein and tie wires welded to both the inner and outer faces of the pipe and extending into the concrete to tie the latter thereto. 2
7. A reinforced concrete pipe having an imperforate sheet metal pipe embedded therein, mesh reinforce spaced from the sheet metal pipe, and also embedded in the concrete, together with wires welded to the face of the pipe and connected to said mesh reinforce, substantially as described. 3

In testimony whereof I have signed my name to this specification.

GEORGE CORRIE BARTRAM.
